US00D783166S

(12) **United States Design Patent** (10) Patent No.: **US D783,166 S**
(45) Date of Patent: ** Apr. 4, 2017

(54) **SURGICAL INSTRUMENT**

(71) Applicant: **NuVasive, Inc.**, San Diego, CA (US)

(72) Inventors: **Bon Champ**, San Diego, CA (US);
James Coleman Lee, San Diego, CA (US)

(73) Assignee: **NUVASIVE, INC.**, San Diego, CA (US)

(**) Term: **14 Years**

(21) Appl. No.: **29/460,276**

(22) Filed: **Jul. 9, 2013**

(51) LOC (10) Cl. **24-02**

(52) U.S. Cl.

USPC **D24/147**

(58) **Field of Classification Search**

USPC D24/466, 146, 147; D15/138, 139;
606/79-81, 84-87, 180

(57) **CLAIM**

The ornamental design for a surgical instrument, as shown and described.

DESCRIPTION

FIG. 1 is a perspective view of a surgical instrument; FIG. 2 is a side view thereof; FIG. 3 is another side view thereof; FIG. 4 is a front end view thereof; FIG. 5 is a back end view thereof; FIG. 6 top view thereof; and, FIG. 7 is a bottom view thereof. The broken lines shown in FIGS. 1-7 illustrate portions of the surgical instrument that form no part of the claimed design.

1 Claim, 3 Drawing Sheets
